UNITED STATES PATENT OFFICE.

EUGENE DENZEL, OF GLEN ULLIN, (DAKOTA TERRITORY,) NORTH DAKOTA.

SALE CARD OR PAMPHLET.

SPECIFICATION forming part of Letters Patent No. 425,496, dated April 15, 1890.

Application filed January 23, 1889. Serial No. 297,283. (No model.)

To all whom it may concern:

Be it known that I, EUGENE DENZEL, a citizen of the United States, residing at Glen Ullin, in the county of Morton, Dakota Territory, have invented certain new and useful Improvements in Sale Cards or Pamphlets; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to sale cards, books, or pamphlets.

The object of my improvement is to provide an effective system of accounts between parties engaged in trade, whereby business may 20 be conducted upon the advance-payment plan, the credit system, or the rebate method, or the combination of any two or all of these systems.

For the above purposes my invention consists in the following combination of parts 25 and devices, a detailed description of which will be given and the features of novelty then set forth in the claims.

Figure 1 represents a plan of my "credit folder," as I term it, spread out or unfolded, it being an outside view. Fig. 2 represents a similar view of the reverse side.

It will be understood that in the normal shape or position of the device the sheets or 35 pages A and B are on the outside, the pages being folded on the lines *a a*.

On the reverse of page B, which is page D, Fig. 2, I have arranged a series of numerals G in series, as shown. There are on this page 40 five series of numerals G in the denomination of cents, each series representing five hundred cents in the aggregate, or five dollars. These series I prefer to arrange along the sides and bottom of the sheet, so as to be 45 within easy reach of a canceling or perforating punch.

In each series there are, preferably, thirty separate amounts or numerals, which, added, make the sum of five dollars. There are three 50 amounts of one cent each, four of two cents,

three of three cents, two of five cents, three of ten cents, four of fifteen cents, four of twenty cents, four of twenty-five cents, two of fifty cents, and one of one hundred cents.

1 represents the space in the upper left-hand corner where the number of the credit-folder may be recorded, and 2 the amount of money in merchandise which the folder represents. Page D may also have printed or inscribed upon it any conditions of purchase 55 or desired information or directions. For instance, I have had printed on it the words "Not transferable," and a statement that the folder is "Issued to Mr. ——, on conditions named on back hereof;" also, the words "In 65 account with ——, dealers in ——," and, also, "Finder will please return this to the above firm." I also prefer to print the words "five dollars" in connection with each series of numerals on said page D. 70

Page E contains a tabulated record of purchases, each of which is to be marked down with the date thereof by the merchant before punching the corresponding amount in the numerals or combination of numerals on page 75 D. Information to this effect is printed on page E, and 33 represent the date and amount columns for carrying out this provision.

Page F contains a note, which, in the credit system, is given by the purchaser of the folder 80 in consideration of the value thereof in merchandise. It is made out corresponding in number and amount to the folder to which it is attached, and it is detached before the folder is given the purchaser and retained 85 by the dealer or merchant. For this purpose I prefer to perforate or indent the line *a*, in order that it may be readily detached.

On page C, the reverse of page F, may be printed a memorandum or receipt for the 90 note, or any other memoranda which may be desirable.

On page A, the reverse of page E, I prefer to print the merchant's name and an advertisement of his business, attractively displayed, as shown. 95

On page B, the reverse of page D, I print, preferably, the terms and rules governing the purchase of these folders. Thus I may print a statement that a rebate of a given percent- 100

um or amount will be allowed if paid for in advance, or that a certain sum or percentum will be deducted if paid within a stated time, and that no deduction will be made if the 5 note be not then paid. There may be a statement also that a certain percentum will be charged on the note after a specified time. On this page I prefer to print also that a given amount in trade will be paid as a rebate on this folder where goods to the amount of a given sum (say twenty-five dollars) have 10 been purchased in cash. Other conditions or attractive advertising matter may be displayed thereon.

15 I have given a detailed description and illustration of my invention; but it will be obvious and readily understood that I may change in many respects the arrangement of my credit-folder. For instance, I may make the 20 folder represent more or less than that amount. The disposition and amount of the separate numerals may also be changed. In like manner the other features of my improvement may be modified or transposed from one page 25 to another. The note F is adapted to fold upon page D, and the latter to fold up against page E, with the note between them, so that the credit-folder presents a compact arrangement and may be readily carried about.

What I claim as new, and desire to secure 30 by Letters Patent of the United States, is—

1. A sale-card or credit-folder comprising a single piece adapted to be folded into three leaves, one leaf bearing a note or "promise to pay," one leaf a series of numerals adapted 35 to be punched out, and one leaf a tabulated statement containing the separate amounts and dates of purchase, substantially as set forth.

2. A sale card or folder composed of leaves, 40 one leaf containing a disposition of numerals adapted to be punched out and another a tabulated statement for the amounts and dates of purchase, substantially as described.

3. A leaf or leaves comprising a leaf on 45 which is printed a detachable note, a leaf or leaves containing a series of numerals adapted to be punched out, and a leaf or leaves containing a tabulated form for recording the dates and the amounts punched out, sub- 50 stantially as described.

In testimony whereof I affix my signature in presence of two witnesses.

E. DENZEL.
